UNITED STATES PATENT OFFICE

CARL WESSEL, OF BORBECK, NEAR ESSEN-ON-THE-RUHR, GERMANY, ASSIGNOR TO
THE FIRM CARL STILL, OF RECKLINGHAUSEN, GERMANY

COKE OVEN AND METHOD OF OPERATING SAME

Application filed October 26, 1926, Serial No. 144,307, and in Germany November 6, 1925.

My invention relates to improvements in coke ovens and method of operating same which are intermittently operated and heated from the side walls, especially to means for withdrawing the gaseous products of distillation from the said ovens or retorts.

The main object of my invention is to greatly enhance the yield of by-products of the ovens both as to quantity and quality.

In the distillation of solid fuel in closed chambers or retorts which are heated from the side walls and operated intermittently, it is already known to withdraw the gaseous products of distillation by suction from the interior of the fuel mass, in order to improve both in quantity and quality the yield in by-products, more particularly in hydrocarbons. In previous constructions of this kind the gaseous product of distillation were generally withdrawn by suction from the interior of the fuel mass over the whole vertical height of the charge, or sometimes at its lowest point, that is close to or through the chamber sole.

The arrangement according to the invention differs from these known arrangements since, in the distillation of solid fuel in chambers or retorts laterally heated and intermittently operated, all the volatile products of distillation are drawn by suction from the upper part of the interior of the fuel, for example by tubes, passages, hollow spaces or the like, which are so arranged that the openings for the entrance of the gas are below the free upper surface of the fuel.

The method of carrying out the process aforesaid and the manner in which it operates are explained by the following description of the course of distillation and coking which takes place in laterally heated and intermittently operated chamber ovens for coke and gas production.

Figs. 1, 2 and 3 of the accompanying drawings, which are vertical cross-sections of a horizontal laterally heated coke oven chamber in different stages of the coking, assist the explanation of these stages and the improvements due to the present invention.

The assumption, which has been verified by experience, is now generally admitted (see

Ullmann's "Encyclopädie der technischen Chemie", vol. 7, page 94) that in a coal charge during the process of coking there are two layers *a* denoted as "plastic stage zones" or "coking seams", parallel to the two heating walls *w* (see Fig. 1), of small thickness (about 30-40 mm.) of coal permeated with thick tar constituents and forming a foaming mass, which as the distillation and coking proceed approach one another and finally meet in the middle of the chamber. On the inner side between these two coking seams, there is a raw, unaltered, moderately soft charge *b* of coal at low temperature, which, even in the immediate neighbourhood of the coking layer, scarcely rises to 100° C.; on the two outer sides there is prepared coke *c* of high temperature up to 1000° C. and more and of very solid dense character, which is permeated by a network of horizontal and vertical fissures extending to a greater or less depth. Between the coke *c* and the surface of the chamber walls *w* there is formed by the shrinkage of the coke a narrow free space *i* along the whole chamber wall.

The extremely abrupt fall of temperature in the direction of the flow of heat transmitted at right angles from the surfaces of the wall into the coal, and which is present at the position of the coking seam, depends on the very strong and sudden heat absorption which is necessary at this place, for the change of state of the volatizable materials, more particularly of the water of moisture and the bituminous particles of the coal. The heat transmitted from the hot walls evaporates the water and tar constituents of the coal. These constituents escape as vapours in the direction of the flow of heat into the interior of the charge of coal, are mainly condensed immediately by passing into the adjacent cooler parts of the charge, and produce in this manner the plastic stage zone or coking seam composed chiefly of bituminous particles.

At the opposite inner surfaces of the coking seams *a* the numerous volatile products of distillation are generated, more particularly steam and tar hydrocarbons. In any case

all these gases and vapours forced into the inner space *b* are relatively cool. For example, water as a liquid can be still found in the interior of this cold charge *b* even when the coking processes are considerably advanced. In the coked parts *c* on each side of the coking seams *a* mainly permanent gases, including hydrogen and more especially the valuable ammonia, are developed. These latter gases are very hot, consequently specifically light, and thereby are by their buoyancy driven from below upwards along the walls of the chamber to the upper surface *d* of the chamber charge.

The coking seams *a* offer great resistance to the passage of the gases. They may be considered almost as gas-tight, so that they are able to a certain extent to shut off the inner space *b* from the outer spaces *c*. This fact gives rise to important results in respect to the static balance between the two columns of gas which have different specific weights and which are present in the inner space *b* on the one hand and in the outer spaces *c* on the other hand.

It can be next seen from Fig. 1 that the spaces *b* and *c* directly communicate at the upper surface *d* of the chamber charge, so that at this level the pressure of the gas column in *b* must be practically the same as the pressure in the gas column in *c*. If it is also taken into consideration that the gases in *b* are specifically heavier than the gases in *c*; and that, consequently, the increase of the static gas pressure in *b* in the downward direction must be greater than the corresponding increase of the static gas pressure in *c*, it is seen that at every level below the upper surface *d* of the charge the static pressure of the gas column in *b* is greater than the static pressure of the outer gas column in *c*. Consequently, there is during the commencing stages corresponding to Fig. 1 in the whole inner space *b* an excess pressure of the gases and vapours in the direction from the interior outwards.

The absolute magnitude of this excess pressure is considerable. If, for example, the average specific weight of the mixture of gas and vapour in *b* at 0° and 760 mm. is assumed to be 1.1 kg. per cubic metre (this corresponds to a mixture mainly consisting of steam and tar vapours), then at the same pressure but at a temperature of 100°, the average weight

$$s_t = \frac{1.1 \times 273}{272 + 100} = 0.81 \text{ kg. per cubic metre,}$$

and if also the average specific weight of the gaseous mixture in *c* at 0° and 760 mm. is assumed to be 0.6 kg. per cubic metre, then at the same pressure but at a temperature of 1000 C., the average specific weight

$$s_a = \frac{0.6 \times 273}{272 + 1000} = 0.13 \text{ kg. per cubic metre.}$$

Under the above conditions, the difference of pressure at a level *H* below the upper surface *d*, according to the known hydrostatic laws, is *H* ($s_t - s_a$). Therefore, for example, if the height of the charge is 3 metres, as it often is in modern chamber ovens, there is at the chamber sole an excess pressure from inwards outwards amounting to $3(0.81 - 0.13) = 3 \times 0.68 = 2$ kg. per square metre = 2 mm. water gauge. Such a difference of pressure produces in this case theoretically a flow of gas at a speed of 7 metres per second and is therefore sufficient to drive considerable quantities of gases or vapours through the fissures and leaky places of the separating layers *a*. Consequently, there is, in a coke oven chamber according to Fig. 1 in which the gas is withdrawn by suction in the usual manner through the oven roof, a flow of gas in the interior of the charge of coal in the direction indicated by the arrows. The cold heavy gases and vapours in the inner space *b* descend and press in consequence of their excess pressure, more particularly in the lower portion of the chamber, through the leaky places and holes of the coking seams *a*, are heated in the outer spaces *c* to a high temperature and rise, due to their buoyancy exerted thereby between the hot walls *w* and the coking seam *a*, partly through the spaces *i* directly along the hot walls, partly through the glowing coke *c* upwards and are finally withdrawn through the oven roof. By the passage through the highly heated coke *c* and through the spaces *i* along the hot walls *w* the hydrocarbons of the gases and vapours are more decomposed, so that more particularly hydrogen and carbon are formed which latter is deposited on the coke.

The valuable gas constituents are in this manner partly converted into permanent gases of little value, partly into elementary carbon. The processes afore described take place at the commencing stages; however, no material changes thereof occur in the interior of the oven during the further progress of distillation and coking. Then the coking seams *a* simply press nearer and nearer together, the gas spaces *b* and *c*, separated by them but communicating at the upper surface, remain in the same condition until the coking seams meet in the middle and the whole process approaches its end.

In the arrangement according to the invention a horizontal suction tube *r*, for example, is provided (see Fig. 2) in the interior of the coal charge *b* at a small distance below its upper surface *d*. This tube *r* extends throughout the horizontal length of the coal charge and is preferably provided at its underside with a continuous slot, as shown, or a row of slots or otherwise formed openings for the gas entrance which are situated over the whole length of the tube or the charge, the

said openings being, at any rate, arranged below the upper surface *d* of the charge.

At the commencement of the working of a freshly charged oven there is, with this arrangement, no material change as compared with the action of the ordinary suction shown in Fig. 1. The coking seams *a* are formed by the heat of the two hot walls *w* in direct contiguity to the hot walls exactly as in Fig. 1, and the spaces *b* and *c* outside the coking seams are in direct connection at the level of the upper surface *d*. In this condition there is evidently at first no essential change in the distribution over the height of the chamber of the gas pressure in *b* and *c* from that previously described in connection with Fig. 1. Consequently, there is established in the commencing stages as shown in Fig. 2 a flow of gas in the interior of the chamber of essentially the same kind as shown in Fig. 1. Cool heavy vapours sink, therefore, in *b*, press through the coking seams *a*, mount upwards in *c*, are heated there and escape from *c* upwards into the free space above the upper surface *d* but must now pass thence—which is the essential new feature—through the middle portions of the upper surface *d* into the space *b*, that is, again into the interior of the coal charge in order to reach the tube *r*, as indicated by the arrows. The last portion of the path of the gases through the upper surface and the top layers of the coal charge to the tube *r* offers a slightly greater resistance than the corresponding path shown in Fig. 1 to the openings in the oven roof; the suction must, therefore, be somewhat greater within the tube *r* than in Fig. 1, that is, the absolute pressure of the gases in *b* at the level of the tube *r* must be somewhat reduced. The absolute pressure of the gases in the outer spaces *c* in direct vicinity of the hot walls *w* is maintained at every working system, by correspondingly controlling the gas suction, so as to maintain it at a constant value and thereby ensure that the gas pressure on the chamber side is practically equal to that on the firing side of the hot walls.

The flow of highly heated gases from the spaces *c* upwards and through the upper surface *d* of the charge back again to the space *b*, due to the arrangement of the suction tube *r* below the upper surface *d* of the charge, has the very important result that this upper surface *d* is coked by passage through it of the highly heated gases, and immediately below it a coking seam is formed of the same kind as the coking seam *a*. It is to be noted that the necessary melting and evaporation of the bituminous particles of the coal takes place at very moderate temperatures of about 300° to at the most 400° C., while the gases from *c* effecting the heating action are at a temperature of about 1000° C. or more. The formation of a coking seam of this kind along the upper surface *d* of the charge of coal has naturally the result that the resistance to the flow of gases passing upwards from *c* back to *b* and into the tube *r* is increased. Therefore, as the operation proceeds the suction in the tube *r* must be progressively increased. Finally, the coking seams *a*, *a'* are completely closed at a comparatively early stage of the coking process by the parts *a'*, *a'* at the tube *r*. This practically complete closure of the coking seams is assisted by the fact that the permeating hot gases which heat the top parts of the charge preferably tend to take the paths through those spaces or holes in the newly formed coking seams which offer the least resistance. At these places the greatest heat is imparted and the progress of the formation of the coking seam most rapid. When this condition, as shown in Fig. 3, is attained, the suction in the tube *r* can and must be further increased, that is, the absolute value of the gas pressure in the inner space *b* is to be considerably reduced. As a consequence of this condition, in all the vertical levels outside the coking seams *a*, *a'* roundabout, the gaseous pressures in the outer spaces *c* and also above the upper surface *d* are greater than the gaseous pressures in the inner space *b*. Consequently, all the gases and vapours developed in the inner space *b*, more particularly the tar hydrocarbons, are led directly into the tube *r* and the passage of these gases and vapours from the cool space *b* to the hot spaces *c* is entirely prevented. Any decomposition and deterioration of these gases and vapours are thereby avoided. The hydrocarbons, more especially the tar oils, are obtained in the condition in which they were originally produced. A tar is obtained which has a great similarity with the so-called primary tar obtained at low temperature distillations. The quantity of the hydrocarbons and of the tar is considerably greater than in the usual manner of withdrawing the gases as shown in Fig. 1. More particularly, the yield in benzol hydrocarbons and in benzines is considerably increased. And also the yield of ammonia is very favourably affected. The ammonia is present, as is well known and mentioned above, during the later stages of the coking predominantly in the spaces *c* filled with glowing coke. In the usual method of withdrawing the gases as shown in Fig. 1 through the chamber roof the ammonia produced must take a path of considerable length, namely the length of the spaces *i* along the highly heated walls *w* before it is removed from the oven chamber. By this passage past the highly heated upper surfaces of the walls and also of the coke itself, a large portion of the ammonia is decomposed and lost. By the arrangement of the suction as shown in Fig. 3 all the gases produced in the outer coke parts *c* are drawn

in the quickest and shortest path through the fissures existing in the coking seams into the cold inner space *b*. This is only possible since, in consequence of the complete closure of the coking seams produced at *a'*, *a'*, a considerably lower pressure can and must be maintained in the inner space *b* relatively to the spaces *c* which fact more than compensates and converts into the opposite direction

10 the hydrostatic pressure differences present in Figs. 1 and 2 within the oven chamber which produce in it the disadvantageous shunt currents.

As is easily seen from the previous description, all the described improvements in working depend essentially on the arrangement of the suction tube *r* and more particularly of its entrance openings in the interior of the coal charge below the upper surface *d*

20 of the same. The carrying out of the process described is obviously not limited to the form of this tube. Other devices for withdrawing the gaseous products of distillation can be arranged at these places which, for example, project from the oven roof downwards to a certain extent into the coal charge and have their gas entrance openings below the charge surface. Under some circumstances, in par-

30 ticular cases, it is sufficient to provide by suitable means and keep open a hollow space or channel within the coal charge which replaces the tube *r*, but this is only possible with certain kinds of coal. The arrangement of all such suction devices in the interior of the coal charge but only at their upper part, in contrast to all other kinds of suction from the interior of the charge, has the extremely practical advantage when these devices are ap-

40 plied to horizontal oven chambers to be discharged in the horizontal direction, that they in no way hinder the application of the usual pusher for discharging the coke. The process can, therefore, be easily applied to existing 45 oven chambers and for this purpose no important reconstruction is necessary at the ovens.

What I claim is:

1. In a horizontal coke oven to produce 50 coke as a final product, a chamber receiving a charge of fuel so as to leave a free gas space adjacent the top and having heated side walls, and suction means disposed in the upper part only of the chamber for withdrawing the 55 gaseous products of distillation, said means having an entrance opening situated below the free upper surface of the charge.

2. In a horizontal coke oven to produce coke as a final product, a chamber receiving 60 a charge of fuel so as to leave a free gas space adjacent the top and having heated side walls and a single suction tube disposed within the upper part of the chamber through which the gaseous products of distillation 65 are withdrawn, the entrance opening of said

tube being situated below the free upper surface of the charge.

3. In a horizontal coke oven to produce coke as a final product, a chamber receiving a charge of fuel so as to leave a free gas space adjacent the top and having heated side walls and a single horizontal suction tube disposed within the upper part of the chamber and having openings situated below the free upper surface of the charge, said tube constituting the sole means for receiving all of the gaseous distillation products at a point adjacent the upper part of the charge.

4. In a horizontal coke oven to produce coke as a solid fuel, a chamber receiving a charge of said fuel so as to leave a free gas space adjacent the top and having heated side walls, and a single horizontal suction tube disposed within the upper part of the chamber and extending longitudinally of the chamber for receiving all of the gaseous products of distillation, the said tube having a gas entrance opening situated in the lower wall of the tube and below the free upper surface of the charge.

5. In a horizontal coke oven to produce coke as a final product having means for drawing off gases, the process of withdrawing such gases from said chamber which consists in charging the chamber with a solid carbonizable material, heating the side walls of said chamber to gradually coke the solid products of the charge and therefore form seams, said heating causing the gases to ascend along said seams, and then withdrawing said gases from the chamber at a point immediately below the upper surface of said carbonizable material.

In testimony whereof I affix my signature. 105
